UNITED STATES PATENT OFFICE.

ROBERT T. BAGBY, OF BIRMINGHAM, ALABAMA, ASSIGNOR OF ONE-HALF TO E. M. KILBY, OF BIRMINGHAM, ALABAMA.

CROSSOVER MINE SWITCH.

Application filed June 9, 1923. Serial No. 644,343.

To all whom it may concern:

Be it known that I, ROBERT T. BAGBY, a citizen of the United States of America, residing at Birmingham, in the county of Jefferson and State of Alabama, have invented certain new and useful Improvements in Crossover Mine Switches, of which the following is a specification.

My invention relates to improvements in cross-over switches especially adapted for use in mines to avoid the dangers resulting from the employment of frogs and switch points interposed in the main track.

One object of my invention is to provide the switch with a pivoted turn-out rail coupled for movement with a pivoted latch for the fixed turn-out rail, said pivot having at one end a point adapted to divert the car wheel from one main track rail thereunto and having at the other end an extension of its thread portion adapted to pass over the other main track rail. This arrangement is important in that all moving switch parts are positively connected for joint operation.

A further object of my invention is to provide incline guides up which the pivoted turn-out rail and the latch rail ride when moved to operating position and which permit them when moved to inoperative position to drop sufficiently to clear the rolling stock.

A further object of my invention is to provide a base plate especially designed and adapted to firmly support on the ties at one end the turn-out track pivot and at the other end to extend under a main track rail and to be interlocked with the end of the siding rail with which the pivoted turn-out rail aligns when in operating position.

My invention further comprises the novel details of construction and arrangements of parts, which in their preferred embodiment only are illustrated in the accompanying drawings, in which:

Fig. 1 shows in plan view my improved cross-over switch; the dotted lines showing the position of parts with the switch open.

Fig. 2 is a perspective view of the pivoted turn-out rail and its supporting base plate preparatory to assembling.

Fig. 3 is a side elevation taken on the line 3—3 of Fig. 1.

Fig. 4 is a cross-sectional view taken on the line 4—4 of Fig. 3.

Similar reference numerals refer to similar parts throughout the drawings.

I have illustrated my invention as designed for and adapted to be used in mines, but its advantages are obviously applicable wherever short turn-out switches are available for use. As illustrated, 1 and 2 represent the main track rails in a mine, and 3 and 4 represent the siding rails leading to a room. The cross ties 5 support the main track and the cross ties 6 support the siding track. The siding rail 3 is mounted at its end adjacent to the track rail 1 on a bracket or base plate 7 to which is pivotally connected a latch rail 8. This latch rail at its free end 9 is straightened and bevelled on the side adjacent to the rail 1 and also has its head or tread sloped downwardly approximately to the level of the rail 1 on which it rests in part when in operating position. This latch rail also rests on an inclined guide or support 10 formed by a strap or bar having an intermediate portion thereof sloped upwardly and joining a horizontal ledge adjacent to the main track rail and supported by a filler 20 attached to the ties. The turn-out rail 11 is provided at its center with a pivot hole 12 drilled upwardly through its base and partly through the web and adapted to receive a pivot pin 13 rigid on the base plate 14. The turn-out rail is formed by bending a single rail on the curve of the radius required for the turn-out to the siding track and at one end the turn-out rail 11 is provided with a bevelled taper point 15 corresponding to the latch rail point 9 in

that it is straightened out and tapered to an edge to abut snugly against the track rail 2 and also has its tread sloping towards its free end substantially to the level of the track 2 when the pivoted turn-out rail is in operating position. This free end of the turn-out rail rests upon an inclined guide 10^a corresponding to 10. At its other end the turn-out rail 11 has its web and base cut away so as to leave an overhung tread portion 16 which is long enough to cross the main track rail 1, when the turn-out rail is in operating position, and to align with the end of the adjacent siding rail 4, which end

is anchored in a socket 17 rigidly attached to one end of the base plate 14 and having adjacent to it a raised support 18 which receives and supports the end 16 of the pivoted turn-out rail. The base plate is provided with a series of inclined guide plates 19 and 19^a formed by heavy metal bars having at one end a flange bolted to the base and joining an upwardly inclined intermediate portion and terminating in a horizontally disposed raised supporting shelf which rests upon a spacer block 20 interposed between it and the base plate. The shelf of the guide 19^a has a shoulder 21 over which the rail 15 drops and which thus serves to prevent it sliding back down the guides under wheel pressure. Three of these inclined guides 19 and 19^a are disposed on one side of the pivot 13 and all have the same direction of inclination, and one incline 19 is disposed on the other side of the pivot and has its incline reversely disposed. The inclines are so disposed that when the pivoted turn-out rail moves to its inoperative position, shown 25 in dotted lines Fig. 1, it is resting on the lower bases of the guides 10, 19 and 19^a, but as it is moved to operating position it rides up the several inclines and in doing so rides up on its pivot 13 which projects high enough to firmly anchor the rail while yet permitting this limited vertical play.

The ends 9 and 15 of the pivoted switch rail and latch rail are connected by a bridle bar 22 having its ends upturned and inserted upwardly through holes in the rail bases and there secured by cotter key or pins. By this means all moving parts of the cross-over switch are coupled for joint and simultaneous movement. A single hold-down 35 bracket 23 is also attached to the base plate in position to engage and overhang one side of the pivoted rail base when raised to operating position. It is to be understood that as many of these supports and inclined guides may be utilized as conditions require.

In operation, having assembled the switch parts in the manner described and provided ample cross ties for securely anchoring the base plate and the bracket 50 7 in position, the switch is ready for operation and it is only necessary for the operator to grasp or kick either free end of the pivoted turn-out rail or the latch rail in the direction desired to cause them to ride up 55 the inclines into operating position with the turn-out rail 11 caught and held by the shoulder 21 and hold-down 23. After lifting the turn-out rail 11 free of its holding means the switch parts can be moved together 60 down their respective inclined supports to inoperative or open switch position. Obviously, where desired, any standard switch operating or locking mechanism will be coupled to any moving part of the 65 switch, but for ordinary mine service this

is not needed. As the pivoted rail is moved towards operating position it rides up inclines which lift its tread extension 16 high enough for it to swing over the main track rail 1 and come to rest aligning with the siding track rail 4 and resting on the supports 10^a, 18, 19 and 19^a which will firmly support it, all presenting flat elevated surfaces of ample width to receive and support the base of the turn-out rail. 75 It is important to note that when the switch is in inoperative position all of its parts drop to a level that will clear all parts of the rolling track.

Though I have described with great particularity the details of the embodiment of my invention herein shown, it is not to be construed that I am limited thereto, as changes in arrangement and substitution of equivalents may be made by those skilled 85 in the art without departing from the invention as defined in the appended claims.

Having thus described my invention, what I claim as new and desire to secure by Letters Patent is:—

1. A cross-over switch comprising in combination with main and siding rails, a pivoted latch rail disposed to connect one siding and main track rail, and a single turn-out rail pivoted at an intermediate point 95 and adapted to connect the other main and siding rails.

2. A cross-over switch in accordance with claim 1, in which the pivoted latch rail has at one end a taper point to co-act with one main rail and at the other end an overhung tread adapted to overlie the other main track rail when the switch is in operating position.

3. A cross-over switch in accordance with claim 1, in combination with means to couple the latch rail and the pivoted turn-out rail for joint movement.

4. A cross-over switch in accordance with claim 1, in combination with a base plate adapted to be mounted on the cross ties and extending diagonally of the main track to support the pivoted turn-out rail throughout its adjusted positions.

5. In a cross-over switch, the combination with main track rails and siding rails, of a pivoted latch rail operable to connect one main and one siding rail, and an intermediate pivoted turn-out rail adapted to connect the other main and the other siding rail, and means to elevate the movable switch rails as they are shifted towards operating position.

6. A cross-over switch in accordance with claim 5, in which the means for elevating both the latch and the pivoted turn-out rail comprises guides disposed transversely of the track and having raised rail supporting ledges each connected to an inclined guide portion.

7. A cross-over switch according to claim 5, in which one rail elevating means comprises an inclined guide terminating at a raised ledge having a shoulder over which the rail drops in seating on the ledge.

8. In a cross-over switch for main and siding rails, a pivoted latch adapted to connect one siding rail and one main line rail, an intermediately pivoted turn-out rail adapted to connect the other siding rail and the other main line rail, a base plate carrying a vertical pivot for the turn-out rail on which said rail is free to rotate and move axially, said base plate comprising inclined track supports disposed to engage and elevate the pivoted rail thereon as it is moved to operating position, and having supporting ledges upon which the rail rests when elevated.

9. A cross-over switch in accordance with claim 8, in which said inclined track supports are disposed on each side of the pivot with their inclines reversed, in combination with a hold-down lug adapted to engage and hold the rail in elevated position on said supports.

10. A cross-over switch in accordance with claim 8, in which said base plate has

its end remote from the pivot extended under the main line rail to be crossed, and means to anchor on said end of the plate the siding rail with which the pivoted turn-out rail is adapted to align.

11. In a cross-over switch, main line and siding rails, a pivoted latch adapted to connect one siding rail and one main rail, a pivoted turn-out rail adapted to connect the other siding rail to the other main track rail, said pivoted rail having one end tapered and bevelled to co-act with the main rail and having its base and web undercut to provide an overhung tread adapted to connect with the siding rail, and a base plate carrying at one end a pivot for the turn-out rail and at the other end a support for its connecting siding rail and overhung tread, said base plate also carrying inclined guides adapted to engage and elevate the pivoted rail as it is moved to operating position.

In testimony whereof I affix my signature.

ROBERT T. BAGBY.
